UNITED STATES PATENT OFFICE

DANIEL SIMON, JR., OF UPTON, MASSACHUSETTS

INFLATED SWIMMING SUIT

Application filed October 8, 1931. Serial No. 567,531.

This invention relates to swimming accessories and particularly to buoyant means to be worn upon the body of the swimmer, and has for its general object to provide a means to reduce the effort expended by the swimmer during his progress through the water.

A further object of the invention is to provide a means to assist the swimmer by supplying artificially additional buoyancy to that naturally supplied by the displacement of water by his body.

A further object of the invention is to provide a device which will present a stream line surface in place of the natural contour of the body, and thereby reduce to a minimum the resistance of the water to forward movement of the swimmer.

A further object of the invention is to provide a swimming device which may be worn upon the body without discomfort, and without causing an awkward or unnatural appearance of the wearer.

A further object of the invention is to provide an aid for swimming which may be secured in proper position upon the body within a special compartment formed in a bathing suit.

A further object of the invention is to provide a swimming apparatus having the qualities above pointed out and which also serves to keep the swimmer afloat in case of emergency.

Other objects and features will more fully appear from the following description in connection with the accompanying drawing, and will be particularly pointed out in the claims.

In the drawing:

Fig. 1 is a cross sectional view through a preferred embodiment of the device secured in position upon the body of the swimmer.

Fig. 2 is a front elevation of the device detached from the body of the swimmer.

Fig. 3 is a cross sectional view through the device on line 3—3 Fig. 2.

It is a well-known fact that the character of the surface and the shape of an object greatly affect the resistance it offers to forward motion in water. A great deal of study and experimentation are devoted to the design of the hulls of every sort of water craft to

increase their speed. Such study and careful design based on laws of hydraulics produce very efficient results. The present invention applies such principles of design in increasing the speed and reducing the effort of the swimmer.

Inasmuch as water is not the natural element for a human being, his body is not particularly adapted to propel itself in a liquid minimum. It requires relatively great effort, therefor, for the human being to travel over a given distance in water. The contour of the front portion of the trunk of the human body is irregular and unsuitable as an aquaplane surface. To remedy this fault and also aid in supporting the body in water a hollow float or casing 1 is constructed to be worn at the front portion of the trunk of the body. The float desirably covers the greater portion of the front of the body extending from the chest substantially to the lower extremity of the trunk and laterally substantially to the extreme sides of the body.

The float is constructed of a front plate 2 and a rear or body plate 3 of any suitable flexible material which is impervious to fluid such as rubber or rubberized fabric. The front plate constitutes the aquaplane surface, while the body plate contacts with the body. The two plates 2 and 3 are joined at their sides to form a fluid tight chamber 4. The body plate 3 is shaped to conform to the contour of the portion of the body which it covers. A plurality of longitudinal ribs 5 extend throughout the length of the float and are secured at their edges to both the front and body plate and extend laterally therebetween. The inner edge 6 of the ribs which is secured to the body plate is shaped to conform to the body contour throughout their length, while the other edge 7 of the ribs is shaped to support the front plate in position to present a stream line surface of the proper shape to reduce to a minimum the resistance to forward movement of the swimmer. The ribs 5 serve also to maintain a fixed relation between the front and body plate.

It is possible to construct the float of material having sufficient rigidity to resist collapse without inflating it. It is desirable,

however, to provide means to inflate the float. Such means may consist of an inlet connection 8 containing a check valve and adapted to be connected to a pump or other inflating means.

5 To provide for even distribution of pressure throughout the float, a plurality of apertures 9 are formed in the ribs 5.

A preferred method of securing the float to the body is to provide a recess or pocket 10

10 in the front section of a bathing suit 11. The pocket 10 may close entirely the float which may be sewed permanently into position within the pocket or one end of the pocket may be fastened with buttons or snap fasteners to permit insertion and removal of the float from the pocket. Instead of a completely enclosed pocket the float may be attached to the bathing suit by means of a plurality of fabric strips or other fastening devices of like character.

The float may be secured also to the body independently of the bathing suit, in which case it may be provided with straps 12 shown in dotted lines in Fig. 1 attached to the sides 25 of the float and passed around the body to be secured at the back of the wearer by means of a buckle 13 or any other suitable fastening means. In such construction the float would be provided also with shoulder straps 14 to prevent the float from slipping downwardly upon the body. The float thus secured to the body is worn desirably beneath the bathing suit directly in contact with the body.

When the device is in position upon the 35 body of the bather and he enters the water, the buoyancy of the float serves to aid in sustaining his body in the correct position for swimming. Much of the effort used in swimming is consumed in the effort of the 40 swimmer to keep afloat. With the use of the present invention practically the total energy of the swimmer may be utilized in propelling himself forwardly. The resistance to the forward movement of the swimmer is reduced 45 also by reason of the stream lining of the front or aquaplane surface of the float. A valuable feature of the device is that in case of emergency, for instance, where a swimmer becomes exhausted or his muscles become in- 50 effective due to cramps, the float serves to maintain his body in a safe position near the surface of the water. A swimmer equipped with such a device is able to attain a speed much greater than has been attained heretofore, and is also enabled to travel greater 55 distances than would be possible without the device.

Having thus described the invention, what is claimed as new, and desired to be secured by Letters Patent, is:

60 1. A buoyant swimming apparatus comprising a body plate shaped to fit the front of the trunk of the body and covering substantially the whole area thereof, a front plate overlying said body plate and secured

at its edges thereto to form a fluid tight chamber therebetween and a plurality of ribs situated between the two plates and secured to said body plate to maintain the contour thereof and secured to said front plate to support 70 the front plate from the body plate in position to present a stream line outer surface which presents a minimum resistance to the progress of the swimmer when in the water and means to secure the apparatus to the 75 body.

2. A buoyant swimming apparatus comprising a body plate covering substantially the whole area of the front portion of the trunk of the body, a front plate overlying, 80 spaced from and secured at its edges to said body plate to form a fluid tight chamber therebetween, a plurality of longitudinally disposed ribs preshaped before assembly and extending laterally between and secured at 85 their edges to said plates, said ribs being formed throughout their length to cause the body plate to assume the contour of the front area of the trunk of the body and to cause the front plate to present a stream line surface to the water and means to secure the apparatus to the body.

3. A buoyant swimming apparatus comprising a hollow fluid tight float covering substantially the front area of the trunk of the 95 body shaped on its inner face to conform to the contour of the body and having its outer face stream lined to present a minimum resistance to the progress of the swimmer through the water, a plurality of ribs extending 100 between the two faces of the float each of said ribs being preshaped before its assembly along its inner edge to conform to the outer face of the float and acting to maintain a fixed spaced relation therebetween, an inflating 105 nipple communicating with the interior of the float operable to be detachably connected to an inflating means and means to secure the apparatus in engagement with the body.

4. A buoyant swimming suit comprising a 110 fabric body covering to be worn upon the body, a body plate of water proof material shaped to conform with the contour of the front area of the trunk of the body, a front plate overlying, spaced from and secured at 115 its edges to said body plate to form an air tight chambered float, a plurality of ribs within said float acting to maintain said front plate in position to present a stream lined surface to the water and to maintain a fixed 120 spaced relation between said front plate and said body plate, and a pocket upon the front portion of said body covering to receive and position said float with its body plate conforming with the contour of the front of the 125 body.

5. A buoyant swimming apparatus comprising a hollow float of a thickness substantially less than its length or breadth having an inner face constructed to conform to and

cover substantially the whole area of the front portion of the trunk of the body and an outer face shaped to present an aquaplane surface adapted to glide through the water with a minimum of resistance, a plurality of longitudinally-disposed ribs within said hollow float extending laterally between the inner and outer faces thereof and preshaped along their inner edges to maintain the inner plate in conformity to the contour of the body and along their outer edges to conform to the contour of the outer face and secured at their edges to said inner and outer faces and means to secure said float to the body of the swimmer.

15 In testimony whereof, I have signed my name to this specification.
